(57) **CLAIM**

We claim the ornamental design for a display with animated graphical user interface, as shown and described.

DESCRIPTION

FIG. 1 is a front view of a first image in a sequence for a display with animated graphical user interface;

FIG. 2 is a front view of a second image thereof;

FIG. 3 is a front view of a third image thereof; and,

FIG. 4 is a front view of a fourth image thereof.

The appearance of the display with animated graphical user interface sequentially transitions between the images shown in FIGS. 1-4. The process or period in which an image transitions to another forms no part of the claimed design. The broken line at the periphery of the figures illustrates the display and the remaining broken lines (including the dashed lines) illustrate portions of the animated graphical user interface. None of the broken lines form part of the claimed design.
